UNITED STATES PATENT OFFICE.

SALVADOR HAYES, OF MACON, NEBRASKA.

MECHANICAL POWER.

SPECIFICATION forming part of Letters Patent No. 724,861, dated April 7, 1903.

Application filed June 28, 1902. Serial No. 113,592. (No model.)

To all whom it may concern:

Be it known that I, SALVADOR HAYES, a citizen of the United States, and a resident of Ma-
5 con, in the county of Franklin and State of
Nebraska, have invented a new and Improved
Mechanical Power, of which the following is
a full, clear, and exact description.

This invention relates to improvements in
mechanical powers, the object being to pro-
10 vide a simple device employing a series of
rolling weights for actuating pumping de-
vices, air-compressors, or similar machinery.

I will describe a mechanical power embody-
ing my invention and then point out the novel
15 features in the appended claims.

Reference is to be had to the accompanying
drawings, forming a part of this specification,
in which similar characters of reference indicate
20 corresponding parts in all the figures.

Figure 1 is a plan view of a mechanical
power embodying my invention. Fig. 2 is a
25 side elevation thereof. Fig. 3 is a detail show-
ing one of the operating-levers employed.

In carrying out my invention I employ a
25 track, here shown as circular and consisting
of an inner member 1 and an outer member
2. These members are spaced apart to re-
ceive actuating devices, as will be hereinafter
described, and of course they are concentric.

30 It is to be understood, however, that the track
may consist of a single member, and therefore
it is to be considered as such.

Mounted to move on the track is a series of
35 weight-rollers 3. These rollers are mounted
to rotate on arms 4, extended outward from
a center post 5, the said arms being adapted
to rotate on the post. The outer ends of the
40 arms connect with a rim 6, which serves as a
band-wheel engaged by a band 7, driven from
any suitable power. Instead of driving the
device by band-power it is obvious that it
may be driven by toothed gearing or the like.

45 Mounted to swing relatively to the track,
and, as here shown, between the two members
1 and 2 of the track and at suitable distances
apart, are actuating-levers 8. These actuating-
levers are fulcrumed at their centers, and
50 each end when depressed or lowered is de-
signed to actuate a pumping rod or pawl 9 or
other device. From the center each lever 8

is arched upward and outward to the ends,
as clearly indicated in Fig. 3.

In operation as the weight-rollers move
around the track they will first engage with
the curved surface at the rear end of a lever, 55
moving the opposite or forward end upward,
causing its rod or pawl to actuate its part.
Then as the roller passes onto the curved por-
tion forward of the fulcrum the forward por-
tion will be moved downward and the rear 60
portion moved upward to actuate its rod,
pawl, or the like.

In a machine of the character described it
is obvious that a very small engine or similar
power will be required to operate the device. 65
The heavy weights serve by gravity as a means
for increasing the effective power, and espe-
cially as upon once starting the device its mo-
mentum will aid in carrying the rollers around
the track. 70

While I have shown a circular track with
the rollers having a continuous motion around
the same, I may in some instances employ a
straight track with a roller or rollers movable
back and forth on the same. 75

Having thus described my invention, I
claim as new and desire to secure by Letters
Patent—

1. A mechanical power comprising a track,
operating-levers pivoted at their centers to 80
the track, the upper edges of said levers at
the front and rear of the pivotal point being
curved upward and then downward to the
ends, and weight-levers movable on said track
for engaging with and operating the levers, 85
substantially as specified.

2. A mechanical power comprising a circu-
lar track, levers fulcrumed on said track, the
fulcrum-point being at the centers of the le-
vers, operating devices attached to the oppo- 90
site ends of the levers, a center post or stand-
ard, arms mounted to rotate on said post or
standard, rollers mounted to rotate on the
arms and engaging on said track, and a rim
attached to the outer ends of the arms and 95
serving as a band - wheel, substantially as
specified.

3. In a mechanical power, a track consist-
ing of two concentric sections, spaced apart,
levers pivoted between the sections, the piv- 100

otal points of the levers being at their centers, actuating devices attached to the opposite ends of the levers, the upper surfaces of said levers being curved upward from the 5 centers, and weight-rollers movable on said track for engaging with and operating the levers, substantially as specified.

In testimony whereof I have signed my name to this specification in the presence of two subscribing witnesses.

SALVADOR HAYES.
